UNITED STATES PATENT OFFICE

2,032,862

DEVICE FOR SEALING-OFF METAL TANKS

William A. Wilkins, Schenectady, N. Y., assignor
to General Electric Company, a corporation of
New York

Application July 29, 1932, Serial No. 626,053

2 Claims. (Cl. 226—82)

The present invention relates to electric discharge apparatus and more particularly to devices for sealing evacuated envelopes which contain said apparatus.

It is customary to use large metal tanks as envelopes for certain types of power-translating devices, such as mercury-arc rectifiers, etc. and these tanks are evacuated and sealed off from the pump. In order to facilitate sealing, it is customary to provide a blown glass portion on the metal tank which is drawn down to an exhaust tube and sealed off when the evacuation process is complete. This blown glass seal is very fragile and presents a structural weakness in an otherwise rugged apparatus.

An object of my invention is to provide an improved seal whereby the blown glass member may be eliminated and the metal container sealed entirely by a metal member. In brief, my invention contemplates the use of a sealing device which is temporarily secured to the metal tank or container and which forces a copper or other metal plug into an exhaust opening in the tank when the evacuation is complete.

The invention will be better understood when reference is made to the following description and the accompanying drawing in which Fig. 1 shows a longitudinal section of the improved sealing device and Fig. 2 illustrates an elevational view of the device.

Numeral 1 designates a portion of a metal tank, the interior of which is to be evacuated. An opening, preferably circular in form, is provided in the tank and to this opening, covering the same, there is secured, preferably by welding, a circular steel flange member 2 provided with a threaded upstanding projection 3 which contains an exhaust opening 4. This opening is preferably chamfered as indicated at 5 on the interior of the tank and is slightly tapered, with the opening of smaller diameter nearer the tank.

The improved sealing device is constituted of a metal member 6, the exterior surface of which may be cut to a hexagonal shape in order to permit the application of a wrench for purposes as will appear hereinafter. The member 6 has a longitudinal opening consisting of two central bores of different diameter, the larger bore being of the same diameter as the opening in the flange member 3. The member 6 is provided at one end with an extension 7, threaded on the interior and adapted to be screwed onto the threaded steel flange. There is an opening extending transversely of the member 6 and communicating with the central bore. Into this

opening is driven a steel tubing 8, slightly chamfered at the inner end and tapering at the other end to make a close contact with a rubber hose (not shown), as will be explained presently. The upper end of the hexagonal member 6, as shown, is turned down to form a seat 9 for a piece of extensible metal tubing 10 such as sylphon or the like, while the interior of the metal member 6 at this end is chamfered, as indicated by reference character 11. The member 10 at the top, 10 carries a metal cap 12 which is provided with a threaded bore 13. This cap is fitted tightly to the tubing 10 by means of a turned-down seat 14 and is chamfered on the interior as indicated by reference character 15. There is secured in 15 the threaded bore 13, a centrally disposed metal ram 16 which extends downwardly, as shown, through the bore of smaller diameter in the metal piece 6 and terminates slightly beyond the annular shoulder formed between the two bores 20 of the member 6. The lower end of the ram 16 carries a spring wire holder 17 in any convenient manner, as for example by a hinge and over this holder there is forced a round sealing plug 18 of a relatively soft metal, such as chromium-plated copper. The plug is drilled at the surface which contacts with the ram 16, the hole being of a size sufficiently small to permit the plug to be pressed tightly over the holder 17 and to be securely attached thereto.

When it is desired to operate the device and the sealing plug 18 has been secured to the end of the ram, the sylphon tube 10 is stretched upwardly and held in that position until it is time to force the sealing plug into the opening of the 35 steel flange. In order to maintain the tubing in this position, there is provided a pair of metal arms 19 positioned on opposite sides of the metal member 6 and pivoted at their lower ends to this member about the screws 20. The upper 40 ends of these arms are cut flat and horizontal, as shown, and are adapted to bear against or engage the lower surface of a circular flange provided on the cap member 12. The length of 45 these arms 19 should be such as to hold the sylphon tubing in the extended position carrying with it, the ram 16 and the attached plug 18. It is apparent that when the device is in this position, the plug 18 is held away from the 50 opening 4 and the preferable arrangement is such that the plug 18, in its upper position, completely uncovers the opening in the horizontally-extending tube 8. The arms 19 are preferably connected together in any suitable manner, for 55

example, by an arcuate strip or yoke 21 of metal which serves as a combined support and handle.

In order to operate the device, after a sealing plug has been placed on the spring wire holder, 5 the device is screwed down firmly onto the threaded portion of the flange 3, a copper gasket 22 being used to provide a more intimate contact. A rubber hose (not shown) is then forced on the tapered tubing or nipple 8 and the tank 1 evacuated in the usual manner. After the proper 10 vacuum has been obtained, and in the case of gas or vapor devices, after the gas or vapor has been introduced, the double-armed lever 19 is released by moving the yoke 21 to the left as 15 shown in Fig. 2, and the atmospheric pressure operating on the cap 12 causes the sylphon to collapse and to force the sealing plug into the opening of the steel flange. In order to prevent the lever from moving a distance more than is 20 necessary, i. e. so that it will just simply clear the cap 12, stop pins 23 may be provided on opposite sides of the member 6. There is also a 25 pair of pins 24 located near the pins 23 to limit the movement of the arms 19 in the other direction.

When the plug 18 has been firmly seated in the opening 4, the cap 12 is preferably struck several blows with a hammer in order to complete the seal between the plug and the opening. 30 These hammer blows are communicated to the plug through the ram 16. The sealing device may then be unscrewed from the tank. As an added precaution, the top of the sealing plug and flange may be soldered.

From the foregoing, it is evident that I have disclosed a sealing device which employs all-metal parts and necessitates in its use, simply a metal flange member welded to the tank and provided with threads. The improved arrangement eliminates the need for any glass seals and consequently, permits the manufacture of highly evacuated all-metal tanks which contain electrical apparatus, electrodes, etc.

What I claim as new and desire to secure by 45 Letters Patent of the United States is:

1. A device for sealing off an evacuated metal tank provided with an opening, said device com-

prising means for holding a sealing plug at a position remote from said opening but in line therewith, said means comprising a hollow metal member which fits over the tank opening, and a collapsible air-tight member which closes the 5 opening in said metal member and which carries the sealing plug, the interior of said member being subjected to the rarefied conditions in the tank and the exterior of said member being exposed to the atmosphere and means for releasing 10 the holding means whereby the sealing plug is permitted to move toward the tank and to be forced into the opening by atmospheric pressure, said releasing means comprising a pair of interconnected arms rotatably mounted on opposite sides of said hollow metal member and adapted to be moved from a position in which they engage the collapsible member to a position 15 entirely free of said member.

2. Apparatus for forcing a sealing plug into 20 an opening in an evacuated metal tank, said apparatus comprising in combination, a metal member having a central aperture and adapted to be secured to the tank in line with said opening, a collapsible metal tubing secured to said member and closed at the end remote from the tank by a cap whereby the interior of said tubing is subjected to the rarefied conditions of the tank and the exterior of said tubing is exposed to the atmosphere, a rod secured to said cap and extending through the aperture in said member, said rod being adapted to receive a sealing plug which is temporarily positioned within the interior of said metal member in line with the opening in said tank, an evacuating conduit secured to said member and communicating with the interior of the tank, a pair of interconnected arms mounted on opposite sides of said member, said arms being of a length sufficient to engage said cap and to hold the collapsible tubing 30 in an extended position, said arms being adapted to be rotated to a position entirely free of the cap whereby the tubing is forced to collapse by atmospheric pressure and the rod member 35 to move toward the tank and to force the sealing plug into the tank opening.

WILLIAM A. WILKINS.
